CLAIM

The ornamental design for a document camera, as shown and described.

DESCRIPTION

FIG. 1 is a front perspective view of a document camera;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a bottom perspective view of a document camera with a lens portion in an angled configuration;

FIG. 9 is a top perspective view thereof, with a lens portion in an alternate angled configuration;

FIG. 10 is a front perspective view thereof showing a neck portion in a bent configuration; and,

FIG. 11 is a front perspective view thereof showing the neck in a closed configuration.

The broken lines depict environmental subject matter only and form no part of the claimed design.
